tion of Delaware

Original application Feb. 26, 1958, Ser. No. 49,807.
Divided and this application Mar. 9, 1961, Ser. No.
64,706

Term of patent 14 years

(Cl. D48—16)

FIG. 1 is a perspective view of a lamp shade, showing my new design.

FIG. 2 is a bottom plan view thereof.

FIG. 3 is a side elevation thereof with portions shown broken away to better illustrate the configurational details.

FIG. 4 is an enlarged fragmentary detail view in side elevation of the cording which forms the side surface of said shade.

This application is a division of my copending application Serial No. D. 49,807, filed February 26, 1958, which application, Serial No. D. 49,807, is a continuation of my earlier filed application Serial No. D. 44,730, filed February 4, 1957.

I claim:

The ornamental design for a lamp shade, as shown and described.
